UNITED STATES PATENT OFFICE.

HERMANN FISCHER, OF NEW YORK, N. Y.

SOUND TRANSMITTING AND RECEIVING DIAPHRAGM.

Application filed January 14, 1925, Serial No. 2,247. Renewed November 23, 1927.

This invention relates to an improvement in sound diaphragms for the transmission, reception, reproduction or amplification of sound waves, and whether the transmission, 5 reception or reproduction is by telephone, radiophone or other mechanism.

In the various devices for transmitting or reproducing sound waves, a diaphragm is employed which is customarily iron, because 10 of the ready action thereon of the magnetic poles. In the use of the ordinary iron diaphragm, there is a constant condition under which some of the tones sought to be reproduced are damped, muffled or distorted. If 15 the iron diaphragm is so constructed as to be suitable for reproduction or transmittal of the high tones, it is not desirable as a medium for the low tones. A physical reason is that when the iron diaphragm is sufficiently 20 resistant for the high tones, it is too resistant for the low tones, because these tones are of slow vibration and low force, whereas the high tones are of high vibration and greater force. The object of the present invention 25 is to provide a diaphragm which is adapted for both the high and the low tones of the scale and which will reproduce both tones without distortion.

The invention will be understood by reference to the accompanying drawings in 30 which—

Figure 1 represents a diaphragm provided with a central disk member, an annular rim and two legs or webs connecting the rim to 35 the central member;

Figure 2 is a cross-section of a diaphragm, the section being at its axis (as along the dotted line 2, Figure 1), the construction being the same as in Figure 1 with the exception that the web is of uniform width 40 and is connected by an eyelet 6 to the disk 5.

Figure 3 represents a modification of Figure 1 in that the number of the connecting legs are increased;

Figure 4 represents a further modification 45 of the structure illustrated in Figure 1.

Unlike the usual sound receiving or transmitting diaphragm, my diaphragm is constructed of two different materials, having 50 different physical response to vibrations.

Referring to Figures 1 and 2, it will be seen that my diaphragm consists of a central disk member 1 of magnetic material,

such as iron, connected by the legs or webs 3 to an annular rim 4. This said structure is superposed upon and preferably firmly united with a disk 5 which may be of non-magnetic material if desired, or material weakly responsive to magnetic waves, as for example duralumin, aluminum, or fibre. 60 In some cases paper stiffened with shellac or other suitable stiffening agent may be employed.

When the disk 5 is made of a metal, as for example aluminum, it is preferable that its 65 thickness be about .001 m. m. or .002 m. m., the iron part of the diaphragm about .009 m. m., although the thickness of the diaphragm members may vary somewhat from these figures without greatly affecting their 70 action.

In connecting the disk 5 to the iron member of the diaphragm, I may, in addition to or in substitution of welding or cementing, employ a mechanical connecting device such 75 as the flanged eyelet 6 shown in the cross sectional view, Figure 2.

The modifications of my device as illustrated in Figure 1, embody the same principle, but those shown in Figures 3 and 4 employ greater areas of the magnetic diaphragm unit. In all cases the high tones are satisfactorily transmitted by the relatively 80 stiff magnetic iron unit, and vibrations of the lower tones are carried to the softer, less 85 resistant member of the diaphragm and are satisfactorily transmitted thereby without distortion.

The annular rim 4 of the magnetic unit of the diaphragm is not essential from the 90 standpoint of operation, but affords a ready means of permitting the diaphragm to be clamped in position in exactly the same manner as the diaphragm now in use.

It will be understood that I have illustrated in the drawings several only of many possible forms of my diaphragm and that those shown in the drawing are illustrative of the principle of my invention, what I claim and desire to secure by Letters Patent 100 being as follows:

1. A sound diaphragm comprising a disk-like member of magnetic material formed with its central area connected to its periphery by spaced webs, and a second disk-like 105 member less resistant to sound waves and ap-

plied to the face of the first member and closing the spaces between the webs thereof.

2. A sound diaphragm comprising a disk of magnetic material having a central area connected to its periphery by spaced webs, and a second disk less resistant to sound waves applied directly to the face of the first disk and co-extensive therewith, the arrange-

ment being such that the peripheries of both disks may be clamped in position by the same means when the diaphragm is employed in a casing.

In testimony whereof, I have signed my name to this specification.

HERMANN FISCHER.
